UNITED STATES PATENT OFFICE.

EUGENE A. RIOTTE, OF DOUGLASTOWN, NEW YORK.

REFRIGERATION APPARATUS.

1,370,153.

Specification of Letters Patent.

Patented Mar. 1, 1921.

Application filed November 28, 1919. Serial No. 341,232.

To all whom it may concern:

Be it known that I, EUGENE A. RIOTTE, a citizen of the United States of America, residing at Douglastown, New York, have 5 invented a new and useful Refrigeration Apparatus, of which the following is a specification.

My invention relates particularly to apparatus of the intermittent absorption type, 10 employing for instance, ammonia.

The main object is to provide simple and inexpensive apparatus, which can be used for instance, for household refrigeration purposes, and which will require a minimum 15 of attention and have a maximum of efficiency.

In its preferred form the complete apparatus is automatic in its action, and entirely avoids the use of valves or other features requiring adjustment or attention. In 20 the form shown ammonia gas is driven off from a still by heat and passes automatically through an evaporator chamber to a condenser. Upon the completion of the distillation and cooling of the still, the liquefied 25 gas is forced back into the evaporator chamber. The evaporation, of course, lowers the temperature and produces the desired cooling, and the gas automatically 30 turns to and is absorbed in the liquid in the still. In this process of distillation the hot gas passes through the evaporator or refrigerating element. For this reason I have provided a special construction of the evaporator-refrigerator, so that the hot gases will 35 have substantially no effect on the refrigerator itself although the construction insures a maximum refrigerating effect during the evaporation and absorption cycle of the 40 operation.

Figure 1 is a diagrammatic view of apparatus embodying the improvements of my invention.

Fig. 2 is a partial front view and partial 45 vertical section view of the evaporator-refrigerator parts of the apparatus.

Fig. 3 is a plan view of the brine tank.

The still-absorber 5 may be of any suitable form. I have shown it in the form of 50 a horizontally disposed cylindrical drum which has been found satisfactory. The evaporator 6 is shown in the form of a vertically disposed cylindrical drum. The condenser 7 is shown in the form of an inclined 55 cylindrical drum. Any suitable form of heater 8 may be employed for heating the

still-absorber and driving off the ammonia gas. Between the still absorber and the evaporator I prefer to locate a trap 9 adapted to contain water. The upper part 60 of the gas chamber of the still-absorber is connected by an inverted U shaped pipe 10 with the lower part of the trap 9, and the upper part of the trap is connected with the upper part of the evaporator by means 65 of a pipe 11. The lower part of the evaporator 6 is connected with the lower part of the condenser by means of pipes 12 and 13. The condenser is located in a cooling tank 14 through which cooling water may be 70 circulated. A circulating pipe 15 has its opposite ends connected to the opposite ends of the still-absorber below the liquid level, and has a considerable part of its length immersed in the cooling liquid of the tank 14. 75 The upper part of the trap 9 is connected by a return pipe 16 leading to the upper end of one leg of the circulator 15 below the bottom of the still-absorber. A drain pipe 17 leads from above the evaporator and discharges into some liquid containing part of 80 the system other than the evaporator and condenser. In the form shown, the drain 17 discharges into the trap 9 below the liquid level. In its preferred form a water 85 jacket 18 may surround the trap 9 so as to keep its temperature down and assist in eliminating water or water vapor from the gas which passes over from the still-absorber. 90

The refrigerator 19 may be of any suitable type. The tank 20 for containing a suitable brine solution has a flange 21 for supporting it in the refrigerator. For convenience in filling the tank, it may be provided with a lateral channel 22 with an entrance inside of the refrigerator having a stopper 23. The evaporator 6 has a flange 24 for supporting it with its lower end arranged in the upper end of the brine tank. 100 Preferably the upper part of the evaporator is surrounded by a cover 25 and heat insulating material 26. A tube 27 is connected to the upper end of the evaporator 6, and carries the connections for the gas 105 pipe 11, the condenser pipe 13, and the drain pipe 17. A partition 28 is located between the pipes 11 and 17, and forms a support for the pipe 12. The brine tank may be provided with one or more chambers 29 110 having a cover such as 30, so that various articles can be placed in a position to be al-

most completely surrounded by the refrigerating liquid and obtain a maximum cooling effect.

During the distillation or heating period, the operation is substantially as follows: The heater causes the liquid in the still to boil and drive off the ammonia gas which passes through the pipe 10 into the trap 9, and then bubbles through the liquid 10 in the trap and passes upward through the pipe 11 into the lower end of the tube 27 and down into the evaporator 6, thence up through the pipe 12 and down through the pipe 13 into the condenser 7, where the gas 15 is liquefied. Of course, more or less water or water vapor is carried over with the gas from the still into the trap 9 and some of it is condensed. When the liquid level in the trap rises above the upper end of the return pipe 16, the excess of water runs back 20 into the still 5. Some of the water vapor however may be carried over into the evaporator. This however cannot collect above the lower end of the pipe 12 but will be 25 forced up the pipe 12 above the partition 28, and will automatically drain back through the pipe 17 into the trap 9, and thence back through the pipe 16 into the still-absorber. The hot gas will continue on its 30 way through the pipe 13 into the condenser 7, where on account of the lower temperature the pressure is the least. On account of the special construction and arrangement of the evaporator and the brine tank, the 35 heated gas has practically no effect on the refrigerator, since the hottest part of the brine surrounding the lower end of the evaporator 6 is at the top and naturally tends to stay there. When the heater 8 is 40 turned off either automatically or by hand, the still cools off and the pressure decreases. The absorption and refrigeration cycle then begins, the gas in the condenser forcing the liquid ammonia up through the pipe 13 and 45 down into the evaporator 6. As the evaporation takes place in the vessel 6, the temperature quickly drops, thus cooling the brine in the upper end of the tank 20. This immediately starts circulation of the brine 50 in the tank 20 since the cooler brine tends to flow down and warmer brine in the bottom tends to flow up. As the gas evaporates from the vessel 6 it passes through the pipe 11, through the trap 9, and pipe 16 into one 55 end of the circulator 15, which of course is filled with the liquid in the still. On account of the fact that the specific gravity of the water and absorbed gas at the lower end of the pipe 16 is less than that of the weaker 60 solution in the still, the liquid circulates through the pipe 15 in the direction of the arrow so that the gas is absorbed rapidly in the reservoir 5.

I claim:—

1. Refrigeration apparatus comprising, 65 the combination of a still-absorber, an evaporator connected to the still-absorber, a condenser connected only to the evaporator so that the gas in passing from the still-absorber passes through the evaporator into 70 the condenser, a refrigerator including a brine tank of considerable depth, the lower end of the evaporator extending only into the upper end of the brine tank, the upper part of the evaporator extending outside of 75 the refrigerator, whereby there is very little circulation of the brine during the heating of the still-absorber and a considerable circulation of the brine during the refrigerating period. 80

2. Refrigeration apparatus including an evaporator vessel having a tube extending from the top thereof with a partition intermediate its ends, a smaller pipe extending from said partition to near the bottom of 85 said evaporator vessel, a gas pipe connected to said tube below said partition, a drain pipe connected to said tube above said partition and a condenser pipe connected to the upper end of said tube and a brine tank 90 below the evaporator vessel, the lower end of said evaporator vessel extending into the upper end of said brine tank whereby the heating of the evaporator vessel has substantially no effect on the temperature of 95 the lower end of the brine tank.

3. In a refrigerator, a reservoir containing a cooling liquid, an evaporator having its lower end in contact with the upper part 100 of the cooling liquid, a still-absorber connection at the upper part of the evaporator and a condenser conduit leading from the lower part of the evaporator.

4. In a refrigerator, a reservoir containing a cooling liquid, an evaporator having its lower end extending down into the upper part of the reservoir in contact with the upper part of the cooling liquid, insulation surrounding the upper part of the evaporator, a still-absorber connection at the upper 110 part of the evaporator, and a condenser conduit leading from the lower part of the evaporator. 105

5. In a refrigeration system of the character described, the combination of a brine 115 tank, an evaporator vessel having its lower end extending only into the upper part of the brine tank, insulating material surrounding the upper part of the evaporator, a pipe connected with the upper part of the 120 evaporator for the passage of gas into and from the evaporator and another pipe extending into the bottom of the evaporator for the exit of gas and the return of liquefied gas. 125

6. In a refrigerator, a brine tank, an evaporator having its lower end connected with the upper part of the brine tank, a still-

- absorber connected to the upper part of the evaporator and a condenser connected to the lower part of the evaporator.
7. In a refrigerator, a reservoir containing a cooling liquid, an evaporator having its lower end in contact with the liquid in the upper part of the reservoir, insulation surrounding the upper part of the evaporator, a still-absorber connected with the upper part of the evaporator and a condenser connected with the lower part of the evaporator and a drain connected with the bottom of the evaporator.
8. In a refrigerator, a brine tank having a filling opening at one side near the top
- 5 and closed at the bottom, an evaporator having its lower end extending into the upper end of the brine tank, a still-absorber connected to the upper end of said evaporator, and a condenser connected to the lower 20 end of said evaporator.
9. In a refrigerator, a brine tank having a compartment in its lower portion, a door for said compartment, and an evaporator having its lower end extending into the 25 upper end of the brine tank, a still-absorber connected to the upper part of said evaporator, and a condenser connected to the lower part of said evaporator.

EUGENE A. RIOTTE.
